MULTIRING BUBBLE PRODUCING TOY

Hung-tu Tseng, New York, N. Y.

Application June 28, 1956, Serial No. 42,079

Term of patent 14 years

(Cl. D34—15)

Fig. 1 is a front elevational view of a multiring bubble producing toy in open position, showing my new design;

Fig. 2 is a similar view, showing the same in closed position;

Fig. 3 is a side elevational view of Fig. 2; and

Fig. 4 is a bottom plan view of the same.

I claim:

The ornamental design for a multiring bubble producing toy, as shown.
